UNITED STATES PATENT OFFICE.

ADOLPH H. KURTH, OF MILWAUKEE, WISCONSIN.

ANCHOR-WINCH FOR SMALL CRAFT.

1,192,077.

Specification of Letters Patent. Patented July 25, 1916.

Application filed April 11, 1916. Serial No. 90,409.

To all whom it may concern:

Be it known that I, ADOLPH H. KURTH, a citizen of the United States, and resident of Milwaukee, in the county of Milwaukee, 5 and State of Wisconsin, have invented certain new and useful Improvements in Anchor-Winches for Small Craft; and I do hereby declare that the following is a full, clear, and exact description thereof.

10 The present invention relates to new and useful improvements in anchor winches more particularly of a type adapted for use on small craft.

It is in general the object of the present 15 invention to simplify the structure and improve the efficiency and the readiness of operation of devices of this character.

It is more specifically an object to provide 20 an anchor winch which has means for securing it to a boat in such manner that the winch is capable of universal pivotal adjustment with respect to its point of attachment to the boat, whereby the drum of the 25 winch may be positioned in proper relation to certain guide pulleys carried on the boat, it being understood that the present structure is more particularly adapted to be secured at the intermediate portion of a boat.

Another object is to provide an exceedingly 30 simple locking pawl for the windlass drum which is at the same time adapted for ready and convenient manipulation to release the drum.

A further specific object resides in the 35 provision of an improved guide roller means for the rope in conjunction with the windlass.

With the above and other objects and advantages in view, the invention resides more 40 particularly in the novel combination, arrangement and formation of parts more particularly hereinafter described and more particularly pointed out in the appended claims.

45 In the drawings: Figure 1 is a side elevational view of a boat with the intermediate portion thereof broken away and showing the improved anchor winch mounted in the boat. Fig. 2 is an enlarged end elevational 50 view of the improved winch. Fig. 3 is a top view of one end portion of the winch showing the improved guide rollers. Fig. 4 is a detailed view taken through the winch on the line 4—4 of Fig. 2, and showing the 55 improved locking pawl. Fig. 5 is a horizontal sectional view taken through the cen-

tral portion of the winch on the line 5—5 of Fig. 2, and showing the general assembly of the winch parts.

Referring now more particularly to the accompanying drawings, the body of the winch comprises a pair of side plates 5 and 6 respectively which are held in spaced parallel relation by the corner bolts 7 passed therethrough, and carrying spacing sleeves 65 8 disposed between the plates. The plate 5 has an outwardly projected central bearing boss 9 and journaled in this boss is a sleeve 10 which forms the hub portion of the locking ratchet wheel 11. The plate 6 is provided centrally with an inwardly projected bearing boss 12 in which is journaled a sleeve 13 which terminates at its inner end flush with the inner end of the boss and which has its other end projected a slight 70 distance outwardly of the plate. The bores of the sleeves 10 and 13 are squared, and slidably passed through these bores is a squared shaft 14 which has its end adjacent the sleeve 10 provided with a head 15 limiting its movement through the sleeve. A drum hub 16 is provided which is disposed between the ratchet wheel 11 and the boss 12 and which has a squared bore whereby 75 it is interlockingly mounted on the shaft 14. 80 The flanges of this hub comprise circular plates 17 fastened to the sides thereof, and these flange plates are provided with centrally squared openings receiving the shaft. An actuating ratchet wheel 18 is provided 85 having a squared opening receiving the end of the shaft 14 adjacent the sleeve 13 and engaged also on this end of the shaft 14 is a locking sleeve 19 provided with set screws 90 20 whereby it may be locked on the shaft. 95 For coöperation with the ratchet wheel 18, an operating lever 21 is provided having its inner end bifurcated to embrace the ratchet wheel, the ends of the furcations journaly receiving the sleeves 13 and 19 respectively. 100 A gravity pawl 22 is carried by the lever for engagement with the ratchet wheel.

By the structure set forth, a definite co-action of parts is provided conducting to a maximum simplicity and economy of structure, and to a maximum readiness of assembly of the various parts. The locking sleeve 19 holds all of the parts described in assembled relation and by removal of the sleeve 19 and withdrawal of the squared 110 shaft all of the parts are mutually detached. The sleeve hub 10 of the locking ratchet and

the spacing sleeve 13 of the actuating ratchet form substantially bearing pintles for the windlass drum, and the spacing sleeve 13 and locking sleeve 19 form the bearings for the furcations of the lever. The drum proper is held properly spaced between the side plates by the ratchet wheel 11 on one side and the bearing boss 12 of the plate 3 on the other side.

10 The pawl for the locking ratchet 11 comprises a bar 23 intermediately pivoted directly under the axis of the windlass and having its head end upwardly inclined and provided with a tooth 24 selectively engageable with the teeth of the ratchet, and the handle end of the pawl bar extends horizontally to a point outwardly of the plate 5 and terminates in a finger piece 25 whereby the pawl may be readily tripped to release the drum. This handle end of the pawl also serves as a weight to urge the tooth 24 into engagement with the ratchet wheel at all times.

25 To provide an anti-friction means for guiding the rope adjacent the winch, a pair of upstanding roller bars 26 are provided at the end of the winch from which the rope normally projects, and these bars are journally mounted by means of pintles 27 which 30 engage in respective bars of vertically alined bearing ears 28 formed on the plates.

Taking up now the means for securing the winch to the side of a boat in a manner permitting universal pivotal adjustment with 35 respect to the point of attachment, the plate 5 is provided with an outwardly projecting ear 29 centrally apertured for coöperation with a similarly apertured ear 30, carried by a clamp member 31, for the reception of a 40 clamping screw 32. This clamp member is of inverted U-shape to embrace the side of a boat and a clamping screw 33 is passed through one leg of the member to clamp the boat between said screw and the other leg of 45 the member. The clamping action procured by the screw 32 permits adjustment in a generally vertical direction, and the clamping action procured by the screw 33 permits pivotal adjustment in a generally horizontal 50 direction, and thus a universal adjustment to a certain extent of the windlass body may be procured to properly position the windlass body relative to a plurality of guide rollers 34 carried by the side of the boat for 55 guiding the cable 35 to the end of the boat. Also the present winch is shown as mounted inboard of the boat, it could as well be mounted outboard if desired.

I claim:

60 1. A winch of the class described comprising a body member provided with a central

bearing, a ratchet wheel, a hub sleeve on the ratchet wheel journaled in the bearing and having a squared bore, a drum including a hub portion having a squared bore, a second 65 ratchet wheel having a squared bore, a spacing sleeve disposed between said second ratchet wheel and the hub portion, a squared shaft passed through the hub sleeve, the drum hub, the said spacing sleeve and the 70 second ratchet wheel, an operating lever journaled on the spacing sleeve, and a pawl on the operating lever for coaction with the second ratchet wheel.

2. A winch of the class described comprising 75 the combination of a pair of side members secured in spaced relation and provided with bearings, a locking ratchet wheel, a hub sleeve for said wheel journaled in the bearing of one side member, and having a squared 80 bore, a drum including a hub having a squared bore, a spacing sleeve journaled in the bearing of the other side member, an actuating ratchet wheel having a squared bore, a squared shaft passed through the 85 said hub sleeve, the drum hub, the spacing sleeve and the actuating ratchet, a holding sleeve on the shaft adjacent the actuating ratchet, an actuating lever having inner end furcations embracing the actuating ratchet 90 wheel and journaled on the spacing sleeve and the holding sleeve, and a pawl on the lever engageable with the actuating ratchet wheel.

3. A winch of the class described comprising 95 a pair of side members secured in spaced relation, a bearing projecting outwardly from one side member, a second bearing projecting inwardly from the other side member, a holding ratchet wheel, a hub 100 sleeve therefor, journaled in the first named bearing, a drum including a hub having a squared bore, a spacing sleeve journaled in the second named bearing and extending outwardly of the respective side member, 105 an actuating ratchet wheel having a squared bore, a squared shaft passed through the hub sleeve, the drum hub, the spacing sleeve and the actuating ratchet wheel, a holding sleeve on the shaft outwardly of the actuating ratchet wheel, an operating lever 110 journaled on at least one of said sleeves, and a pawl carried by the lever and engageable with the actuating ratchet wheel.

In testimony that I claim the foregoing I 115 have hereunto set my hand at Milwaukee, in the county of Milwaukee and State of Wisconsin, in the presence of two witnesses.

ADOLPH H. KURTH.
